Basil D. Huff, Wilkes-Barre, Pa. (½ Charles Sonnenreich, 1501 Broadway, New York, N.Y. 10036)

Filed Dec. 6, 1966, Ser. No. 4,932

Term of patent 7 years

(Cl. D2—287)

FIG. 1 is a side perspective view of a slipper showing my new design, the side opposite being substantially similar thereto.

FIG. 2 is a bottom plan view.

FIG. 3 is a plan view thereof in open flap position with the tongue insert and laces removed.

FIG. 4 is the tongue portion of the slipper shown in FIG. 1 removed from the slipper.

I claim:

The ornamental design for a slipper, substantially as shown and described.
